(57) **CLAIM**

The ornamental design for a bow grip as shown and
described.

DESCRIPTION

FIG. 1 is a rear, right perspective view of a first embodiment
of my new design for a bow grip.

FIG. 2 is a front, right perspective view thereof.

FIG. 3 is a rear elevation view thereof.

FIG. 4 is a front elevation view thereof.

FIG. 5 is a left elevation view thereof.

FIG. 6 is a right elevation view thereof.

FIG. 7 is a top plan view thereof.

FIG. 8 is a bottom plan view thereof.

FIG. 9 is a rear, left perspective view of a second embodiment
of my new design for a bow grip.

FIG. 10 is a front, left perspective view thereof.

FIG. 11 is a rear elevation view thereof.

FIG. 12 is a front elevation view thereof.

FIG. 13 is a right elevation view thereof.
